Primary Examiner—Raphael Barkai*Assistant Examiner*—Randall H Gholson(74) *Attorney, Agent, or Firm*—Faegre & Benson, LLP(57) **CLAIM**

The ornamental design for glove pocket, as shown and described.

DESCRIPTION

FIG. 1 is a front and top right side perspective view;

FIG. 2 is a front and top left side perspective view;

FIG. 3 is a front and top right side perspective view;

FIG. 4 is a back and bottom right side perspective view.

FIG. 5 is a back and bottom left side perspective view; and,

FIG. 6 is a side perspective view.

The broken lines shown in the drawings are directed to features not claimed.
